STRUCTURE

Marshall K. McCosh, Reisterstown, Md.

Application March 13, 1933. Serial No. 660,586

15 Claims. (Cl. 189—86)

Broadly, the object of this invention is to equip parts or articles used for construction and assembling with means for covering any or all joints created by the placement of said parts.

5 This object is attained by equipping such parts with one or more pieces of sheet metal, the pieces of sheet metal being fixed to the said parts.

The accompanying drawing shows my invention embodied in a structure used for (Figures 10 1 to 8, inclusive) sheet metal siding, and for (Figure 9) a sheet metal window-sill, in a manner that seems to me now to be the preferable one.

Figure 1 is a perspective of a structure for use 15 as a sheet metal siding. It shows the structure as it is made for shipping to "the job".

Figures 2 to 6, inclusive, illustrate a method 20 of covering the joint created by the placement side by side of two of the siding structures: Figures 2 and 3 illustrate the forming "on the job" of a sheet metal strip at the two sides of the structure before the structure is placed on the side of a building, and Figures 4, 5 and 6 illustrate the forming "on the job" of the sheet metal 25 strips of two adjacent structures after they have been fastened to the side of a building, this forming covering the joint.

Figure 7 is a plan view of a number of the 30 siding structures fastened on a side of a building and having their joints covered as illustrated in Figure 6. (In this case the height of the side of the building requires only two lengths of the structures, and on the structures of the bottom row there are no bottom strips 2, and 35 the side strips 3 and 4 extend only to the bottom edge of the main part 1 of the structure.)

Figure 8 is a perspective showing adjacent corners of four of the siding structures placed adjacent each other in the same plane, with the 40 sheet metal strips covering the four joints and the side strips formed to the stage of their formation illustrated by Figure 4.

Figure 9 is a cross-section of a structure in the form of a formed sheet metal window-sill. Part 45 of the sheet metal strip 13 is shown bent downward to cover the joint between the window-sill and the siding 16. The bent-downward part of the metal strip 13 was in the position shown by the dot-and-dash lines at 15 when the structure 50 was made.

The structure shown embodied in Figure 1 comprises a rectangular main part 1 of flat sheet metal and three rectangular sheet metal strips 2, 3 and 4, which sheet metal strips are of a degree of rigidity less than that of the sheet metal

part 1. Metal strip 2 is lapped over the bottom edge 5 of main part 1, and parallel thereto, and the lap is welded to main part 1 from side edge 6 to side edge 7 as indicated by the short matted lines. Metal strip 3 lies flat on the main part 1, 60 and parallel thereto, close to side edge 6 of said main part 1; the metal strip 3 has its upper edge even with the upper edge of main part 1; it also covers the end of metal strip 2, and extends downward beyond metal strip 2. Metal strip 3 is welded to main part 1 and metal strip 2 from its edge adjacent edge 6 of main part 1 inward a short distance as indicated by the short matted lines. This welding is line welding and is a narrow "ribbon" of welding from the top of main part 1 70 to the bottom of metal strip 2. The welding of metal strip 2 to the bottom of main part 1 is, also, line welding. I hereinafter term metal strip 2 the bottom strip 2, and metal strips 3 and 4 side strips 3 and 4. Side strips 4 likewise lies, 75 and is welded at the opposite side edge 7 of main part 1. There is a slight jog in side strips 3 and 4 where they lap over bottom strip 2, but as these two jogs effect the shape of the structure when formed and the forming of the side strips 3 and 4 so little, it is not taken into account in this specification. There is a hole 8 through main part 1 at its upper edge, and three holes 9 through main part 1 at each of its two side edges, 6 and 7, through which nails or rivets are run for 85 fastening the structure to a side of a building.

The method of covering the side joints illustrated by Figures 2 to 6, inclusive, is this: Just before the structure is applied to a side of a building, the side pieces 3 and 4 are folded over flat on 90 themselves at the inner edge of the welded "ribbon" so that the side pieces 3 and 4 extend beyond the edges 6 and 7 of the main part 1 as illustrated by Figure 2, the folding movement being indicated by the arrow. Then the parts of 95 the side pieces 3 and 4 that extend beyond the edges 6 and 7 are bent upright, at right-angles to main part 1, with their outside surfaces 10 and 11 perpendicularly above side edges 6 and 7, respectively. Then before, or after, the structure is applied to a side of a building the flat folds are opened up wide enough to permit the driving of 100 nails or rivets through holes 9 and then the folds again closed flat over the nails or rivets. This bending, and subsequent opening up of the flat folds, is done with tinners' bending irons or other suitable tools. Or, the bending of one side strip can be deferred until the structure is applied to the side of a building adjacent another structure 105 and nailed or riveted to the building; the side 110

on which the bending is deferred being the one that is not yet adjacent another structure. Two of the structures with their side pieces formed as illustrated by Figure 3, and adjacent each other 5 at their sides, are illustrated by Figure 4, this Figure 4 representing only the joint created by the edge 6 of one of the structures being adjacent the edge 7 of the other structure, together with the part of each structure contiguous to the 10 joint. The next stage of the forming of the side pieces is illustrated by Figure 5: here the free (upright) ends of the side strips 3 and 4 have been folded over to the right and downward in a tight fold, the folding movement being indicated by 15 the arrow. The next stage, as illustrated by Figure 6, has been reached by folding to the right, as indicated by the arrow, the fold illustrated by Figure 5. This bending of the side pieces together into a fold covers the joint in a manner satisfactory for a vertical or partly-vertical joint in siding exposed to the weather, although soldering of the formation along the line indicated at the letter S in Figure 6 is advisable in some cases. The soldering may consist simply of spots of solder spaced along the line indicated at the letter 20 S or continuous soldering.

In covering a side of a building with these siding structures, one structure is first nailed or riveted through holes 8 and 9 to the bottom of 30 the side of the building. Each of the structures for the bottom row may have the bottom strip 2 omitted and the side strips 3 and 4 may end at the bottom edge 5 of the main part 1 when manufactured, as is shown in Figure 7. Also, the 35 side strips 3 and 4 may be cut off with tinners' snips even with the bottom edge of bottom strip 2 if desired. Or, for the bottom row, structures exactly like that shown in Figure 1 may be used. Either before or after the first structure is applied 40 to the side of the building, the side strips 3 and 4 can be formed as illustrated by Figures 2 and 3 and described above. Then other structures can be applied in the same way adjacent each other so that they will be disposed as indicated by Figure 45 8, which shows a corner of each of four structures where they join. It will be noted that the four side edges 6 and 7 adjacent each other are on a straight line; and that the four edges, consisting of the two bottom edges 5 and the two upper 50 edges, adjacent each other are, also, on a straight line perpendicular to the straight line of side edges 6 and 7. Also it will be noted that the bottom strip 2 of each structure, together with the bottom end of side strips 3 and 4, overlaps 55 the structure immediately below it, with the upright part of each of the side strips 3 and 4 disposed on the outside of the upright part of each of the side strips 3 and 4 of the structure immediately below it. This disposition of the side strips throws them slightly out of line, but not to an extent that interferes seriously with the placement of the structures or the bending of the side strips, and the matter is, therefore, not taken into account in this specification. The side 60 strips 6 and 7 in Figure 8 are at the stage of bending illustrated by Figure 3. The side strips are then bent through the stage illustrated by Figure 5 to the stage illustrated by Figure 6. The vertical joint can be made at the corner of a 65 building also.

There can, of course, be variations in the form and construction of this siding structure within my invention. To mention one variation: the main part 1 need not be flat.

70 75 The structure shown in cross-section in Fig-

ure 9 comprises a formed sheet metal window-sill 12, which is the main part of the structure, and a sheet metal strip 13 line welded thereto along a line that will be at the joint between the structure and the siding of a building when the structure is placed as a window-sill in a building, the line being indicated at 14, along which line 14 strip 13 is shown bent downward at right-angles to its original position, its original position being indicated by the dot-and-dash line at 15. The structure is made with the strip 13 in its said original position, and the strip 13 is bent downward after the structure is put in place in a building. The siding of the building is indicated by the dot-and-dash lines at 16. The siding may or may not be of metal. The strip 13 in its bent-downward position covers the joint created by the placement of the structure adjacent the siding 16. Strip 13 could be welded to the window-sill 12 along a line in the dot-and-dash position 15 and the edge 17 of the strip bent downward outside the siding.

These two embodiments of my invention indicate some uses to which it can be put in construction work. There are also other fields in which the invention can be used to advantage.

The main part of such a structure need not be of metal, or need it be of sheet form. It can be a block or other shape or article. It can be, for instance, a furnace or stove part where it is desired to increase the resistance to the passage of air through the joints thereof. Any method that will fix the sheet metal strips to the main parts may be used, welding or other method. The fixing may be done in a factory or shop or "on the job" on the site of a construction or assembling job, but, as a rule, a more workmanlike job and economical job of fixing can be done in a factory or shop.

I claim:

1. A construction member having a strip of sheet metal lying against said member and secured contiguous to an edge of said member along a line parallel to and contiguous to an edge of said strip, the said strip not extending beyond the contiguous edge limit of the said member widthwise of said strip, whereby the said strip may be formed over a joint to cover same by displacement of said strip along the line of attachment.

2. A construction member as set forth in claim 1, the strip thereof being of a degree of rigidity less than that of the said member.

3. A construction member having a piece of sheet metal lying against said member and secured contiguous to an edge of said member along a line parallel to and contiguous to an edge of said piece, the said piece not extending beyond the contiguous edge limit of the said member widthwise of said piece, whereby said piece may be formed over a joint to cover same by displacement of said piece along the line of attachment.

4. A construction member as set forth in claim 3, the piece of sheet metal thereof being of a degree of rigidity less than that of the said member.

5. A construction member having a strip of sheet metal lying against said member and secured contiguous to an edge of said member along a line parallel to and contiguous to an edge of said strip and extending the entire length of said edge of said member, the said strip not extending beyond the contiguous edge limit of the said member widthwise of said strip, whereby the said strip may be formed over a joint to cover

- same by displacement of said strip along the line of attachment.
6. A construction member as set forth in claim 5, the strip of sheet metal thereof being of a degree of rigidity less than that of the said member.
7. A construction member having a piece of sheet metal lying against said member and secured contiguous to an edge of said member along a line parallel to and contiguous to an edge of said piece and extending the entire length of said edge of said member, the said piece not extending beyond the contiguous edge limit of the said member widthwise of said piece, whereby said piece may be formed over a joint to cover same by displacement of said piece along the line of attachment.
8. A construction member as set forth in claim 7, the piece of sheet metal thereof being of a degree of rigidity less than that of the said member.
9. A siding having a strip of sheet metal lying against said siding and secured contiguous to an edge of said siding along a line parallel to and contiguous to an edge of said strip, the said strip not extending beyond the contiguous edge limit of said siding widthwise of said strip, whereby said strip may be formed over a joint to cover same by displacement of said strip along the line of attachment.
10. A siding as set forth in claim 9, the strip of sheet metal thereof being of a degree of rigidity less than that of the said siding.
11. A siding having two strips of sheet metal lying against said siding, each of the two strips being secured contiguous to an edge of said siding, the two edges of said siding being opposite each other, along a line parallel to and contiguous to an edge of each of said two strips, each of the said two strips being within the edge limit of said siding contiguous that one strip widthwise of that one strip, whereby each of the said two strips may be formed to cover a joint created contiguous the respective said edge.
12. A siding as set forth in claim 11, the strips of sheet metal thereof being of a degree of rigidity less than that of the said siding.
13. A siding as set forth in claim 11, but having, also, a strip of sheet metal lying against it and secured along a line parallel to and contiguous to a third edge of said siding, whereby the last-mentioned strip may be made to cover a joint contiguous said third edge.
14. A window-sill having a strip of sheet metal lying against said window-sill and secured contiguous to an edge of said window-sill along a line parallel to and contiguous to an edge of said strip, the said strip not extending beyond the contiguous edge limit of said window-sill widthwise of said strip, whereby said strip may be formed over a joint to cover same by displacement of said strip along the line of attachment.
15. A window-sill as set forth in claim 14, the strip of sheet metal thereof being of a degree of rigidity less than that of the said window-sill.
